UNITED STATES PATENT OFFICE.

BENJAMIN WARDWELL, OF PROVIDENCE, RHODE ISLAND.

CULINARY APPARATUS.

Specification forming part of Letters Patent No. **89,613**, dated May 4, 1869.

To all whom it may concern:

Be it known that I, BENJAMIN WARDWELL, of the city and county of Providence, and State of Rhode Island, have invented a new and useful Improvement in Boilers for Culinary Purposes; and I do hereby declare that the following is a full, clear, and exact description of the same, reference being had to the accompanying drawings, making part of this specification, in which—

Figure 1 is a vertical section of my improved boiler or culinary apparatus. Fig. 2 is a perspective view of the improved portion of the same.

Similar letters indicate corresponding parts in both the figures.

My invention consists in constructing the boiler with a chamber beneath and around the pit or portion which enters the hole in the stove-plate, so that the steam which is generated by the culinary process may be conveyed through a suitable tube, extending from the top of the boiler into the said chamber beneath, and thence escape into the stove or chimney instead of into the stove-pipe or into the room, as heretofore.

In the drawings, A is the boiler, such as is ordinarily used upon a stove, the top plate of which is represented by the lines marked D D in Fig. 1, for general culinary purposes. Upon one side of the walls of the said boiler there is cast or otherwise formed a tube, G, opening near the top into the interior of the boiler, to receive the steam and fumes generated in the vessel, and opening at the bottom into the recess or chamber E, which may be formed beneath the bottom of the boiler by extending the walls or shell A of the boiler

below the bottom surface of the same to the extent, say, of three-eighths of an inch. This, it will at once be seen, elevates the bottom of boiler from contact with the stove-plate D, upon which it rests while in use over the fire, and thus affords a space, E, between the said bottom and stove-plate, into which the steam may be conducted by a tube like G from the top of the boiler, so that the steam will escape into the stove as fast as it is generated, at the same time furnishing a greater fire-surface on the bottom of the boiler than is possible with the bottom of the boiler resting flat and closely upon the stove-plate, as in the ordinary construction of such boilers and apparatus, which exposes to the action of the fire only so much of the pit L as extends beneath the stove plate within the boiler-hole.

Separately the tube G for conducting the steam from the top to the bottom of the boiler is not claimed.

Claim.

A boiler for culinary purposes made substantially in the manner herein described, so that there shall be a space or chamber, E, formed between the bottom of the boiler and the stove-plate, into which the steam passing from the boiler through the pipe or conduit G is discharged, as and for the purposes shown and set forth.

In testimony whereof I have signed my name to this specification before two subscribing witnesses.

BENJAMIN WARDWELL.
